TRIVALENT COMPOUNDS OF TITANIUM AND
METHOD OF MAKING SAME

Eugene Wainer, Cleveland Heights, and Samuel Z. Cardon, Cleveland, Ohio, assignors, by mesne assignments, to Horizons Titanium Corporation, Princeton, N. J., a corporation of New Jersey

No Drawing. Application January 17, 1952,
Serial No. 266,994

7 Claims. (Cl. 23—14)

1

The chemistry of the compounds of titanium in which the titanium exists in stable form at a valence less than 4 is obscure and very little known. Trivalent titanium compounds are important in the dye industry and are promising as a source of feed to reactions used for the preparation of metallic titanium, particularly through the medium of electrolysis. Economical methods of preparation of a variety of trivalent titanium compounds of titanium have not been available; and more important, such compounds have not been made in stable form in condition such that they will remain stable on exposure to the atmosphere. Finally and most important, trivalent compounds in solid form would offer a particularly useful type for commercial purposes, and particularly if such solid forms melt at relatively low temperatures without decomposition.

In accordance with the present invention trivalent fluorine compounds of titanium are prepared in novel manner; and particularly alkali fluotitanates of titanium in which the titanium exists in a valence of 3. We have methods for making stable trivalent compounds of titanium by relatively simple reactions. In addition, we have also found means for preparing two novel compounds of trivalent titanium which are commercially useful. Other objects and advantages of the invention will be seen from the following description.

To the accomplishment of the foregoing and related ends, said invention then comprises the features hereinafter fully described and particularly pointed out in the claims, the following description setting forth in detail certain illustrative embodiments of the invention, these being indicative, however, of but a few of the various ways in which the principle of the invention may be employed.

Our novel methods of procedure were originally devised for preparation of the trivalent titanium compound K_2TiF_5 . We have also been able to prepare the novel compounds $K_2Ti_2F_8$ and K_3TiF_6 . In these the titanium exists in a valence of three; but more important is the fact that these compounds are prepared such that exceptional stability is found to exist so that the titanium compound oxidizes with difficulty.

We obtain our novel compounds and results through the medium of reaction of appropriate fluorine compounds on titanium monoxide. Titanium monoxide is a hard golden brown colored derivative of titanium. The material is a fairly good electrical conductor and the ostensible valence of titanium in this compound is 2. On heat-

2

ing this compound in suitable containers with the appropriate fluorine derivatives, a stable compound of titanium can be obtained and hydrogen is evolved in the reaction. This would indicate that the titanium present in the titanium monoxide is present in the valence of 2. Effective compounds for the purposes of this invention are the alkali metal compounds, and preferably sodium and potassium compounds.

10 We have found a general procedure whereby these trivalent compounds of titanium can be made. In general, we react titanium monoxide with two fluorides, one an alkali metal fluoride, and the other an acid fluoride of a base of the 15 class consisting of NH_4 and elements of periodic group I whose atomic weight is less than 40, that is, sodium, potassium, lithium and ammonium acid fluorides. Thus, it may involve treatment of the titanium monoxide with hydrofluoric acid 20 in a controlled atmosphere, then adding the proper quantity of an alkali fluoride such as potassium fluoride or sodium fluoride, evaporating to dryness in a controlled or inert atmosphere and then heating to fusion. Again it may involve the use of ammonium acid fluoride and 25 potassium fluoride or other alkali fluorides mixed in dry form with the titanium monoxide and then heating. It is preferable again that this heating take place in a controlled atmosphere 30 such as nitrogen to prevent the access of oxygen during this heating step. Products of such a reaction are the alkali fluotitanates in which the titanium is present in the valence of 3, water, ammonia, and hydrogen, and all of these latter three 35 pass off as gases. If the amounts of potassium fluoride or other alkali fluorides are proper, stable compounds of formula K_2TiF_5 , K_3TiF_6 , or $K_2Ti_2F_8$ may be made. The latter two compounds are more stable on fusion than the K_2TiF_5 . Also it 40 may involve the use of mixtures of potassium acid fluorides or other alkali acid fluorides plus an extra amount of a normal alkali fluoride plus the finely powdered titanium monoxide. This mixture is subjected to heat in an inert or controlled atmosphere and the said product compounds are obtained with the concomitant evolution of water vapor and hydrogen. Of the three 45 forms of reagent described above, the latter two are preferred. The alkali acid fluoride compounds may be employed in different formulae, of which, for example, the KHF_2 compound and the K_2HF_3 compound are typical. For these types of reactions, the K_2HF_3 compound is preferred since it is commercially available at low 50 cost.

The containers useful for making this type of preparation may be nickel, copper, or graphite. In general, graphite is preferred. Both the nickel and the copper materials have to be specially surfaced in order that the reaction proceed as indicated. This method of preparation involves the boiling of concentrated hydrofluoric acid in such crucibles for a period of a few minutes, then pouring out the hydrofluoric acid and evaporating the liquid film thus obtained to dryness and finally baking so as to insure the formation of the chemically stable difluorides of nickel or copper on the surface. In order that this type of treatment be avoided, dense graphite may be used if it is inserted in a metal container which prevents access of air to the graphite when it is heated. The graphite container is fitted with a tight cover containing an inlet and outlet. The input consists of dry pure nitrogen, and the outlet is made sufficiently narrow in diameter so that oxygen cannot diffuse back into the contents of the crucible while the material is being heated.

In carrying out the reactions indicated in the foregoing, the various ingredients are mixed in dry form and then put in the crucible. The mixture is then heated to a temperature range below volatilization of the fluoride, viz., around the boiling point of water, i. e., between 100 and 125° C., for a period of 15 to 25 minutes. The purpose of this preliminary heating is to make certain that most of the relatively expensive fluorine compound which is present is not decomposed and volatilized prematurely before it has an opportunity to react with the titanium compound present. After this period of heating is completed, the temperature is raised to about 400° C. and the reaction continued until all traces of gases such as hydrogen, ammonia, or water are eliminated. Both phases of the reaction, that is the preliminary heating and the final heating, are carried out in an inert atmosphere, such as nitrogen, nitrogen being fed into the reaction zone at the rate of 1 to 2 liters per minute. The temperature of 400-500° C. is sufficient to carry the reaction to completion and the end product of the reaction on cooling is usually in the form of a dark blue, purple, or purplish brown sintered mass. On exposure to the air, this sintered mass does not exhibit hygroscopic properties and is stable for further handling.

The following examples are illustrative of our method:

Example 1.—175 grams of ammonium acid fluoride (this is slightly more than the theoretical amount in that the ammonium acid fluoride used generally contains a small amount of water of hydration) were mixed with 135 grams of substantially pure titanium monoxide and 116 grams of KF. Titanium monoxide was in the form of -200 mesh powder. The mixture was then put in a graphite crucible fitted with an outside nickel liner and a closely fitting top. An inlet tube was fastened through the lid, and an outlet port roughly $\frac{1}{4}$ " in diameter was also provided for in the lid. Pure nitrogen was fed into the crucible at the rate of about 1 liter per minute. After all the air had been displaced from the crucible, the assembly was heated to about 120° C., and as the temperature became uniform the temperature was maintained for about 20 minutes. After this preliminary heating period was completed, the temperature was raised to 500° C. In the course of raising the temperature of the container to this range, a noticeable evolution of water and ammonia occurred as determined by the odor and ap-

pearance of the gas. Substantial amounts of hydrogen were also evolved and if a lighted flame were brought in the vicinity of the port and the reaction were carried out in the absence of nitrogen, an explosion could result. The reaction was continued until all evidence of steam or ammonia evolution ceased. This usually requires an hour of heating at a temperature of 500° C. The reaction mass was then cooled down to room temperature under the atmosphere of nitrogen, and the contents on opening the crucible were found to be a sintered dark purplish mass weighing 325 grams. In view of the ingredients which were used, this is practically a 100% yield of the novel compound $K_2Ti_2F_5$.

Example 2.—The ingredients and the reaction mixture were the same as in Example 1 except twice as much potassium fluoride was used, equivalent to 322 grams. 440 grams of the dark purple compound resulted, which is equivalent to a substantially theoretical yield of the compound K_2TiF_5 .

Example 3.—Same as in Example 1 except that 350 grams of potassium fluoride were used and the same procedure was carried out as before except that 560 grams of product were obtained equivalent to the compound K_3TiF_6 . The compounds K_3TiF_6 and the compounds $K_2Ti_2F_5$ may be heated to fusion and on cooling are found substantially unchanged. If the compound K_2TiF_5 is heated to fusion, some decomposition, possibly evolution of TiF_3 or of TiF_4 takes place, as apparent from changes exhibited, and established by analysis on cooling to room temperature.

Example 4.—Same as in Example 1 except that 84 grams of sodium fluoride were used in place of the potassium fluoride. 295 grams of product were obtained, equivalent to the compound $Na_2Ti_2F_5$.

Example 5.—295 grams of the compound KF_2HF and 58 grams of potassium fluoride were mixed with 132 grams of titanium monoxide as in the previous examples. This mixture was heated as before through the two temperature ranges in an atmosphere of nitrogen. 440 grams of product resulted, substantially equivalent to 100% yield of the compound $K_2Ti_2F_5$.

Example 6.—294 grams of the compound KF_2HF + 175 grams of potassium fluoride + 132 grams of titanium monoxide were thoroughly mixed and heated in an atmosphere of nitrogen as in Example 1. 560 grams of product resulted, equivalent to the compound K_3TiF_6 which is substantially 100% yield.

Example 7.—Same as in Example 5 except that 42 grams of sodium fluoride were used in place of the 58 grams of potassium fluoride. 410 grams of product resulted, equivalent to practically 100% yield of the compound $Na_2Ti_2F_5$.

Example 8.—190 grams of the compound NaF_2HF were mixed with 42 grams of NaF and 132 grams of TiO . The procedure in accordance with Example 1 was followed and 380 grams of product obtained, substantially equivalent to a theoretical yield of the compound $Na_2Ti_2F_5$.

Example 9.—295 grams of the compound KF_2HF + 175 grams of the compound KF + 135 grams of titanium monoxide of -200 mesh particle size were mixed together and treated as in Example 1. 560 grams of product resulted, substantially equivalent to 100% yield of the compound $K_2Ti_2F_5$.

Other modes of applying the principle of the invention may be employed, change being made as regards the details described, provided the

features stated in any of the following claims or the equivalent of such be employed.

We therefore particularly point out and distinctly claim as our invention:

1. The method of producing alkali metal fluotitanates in which the titanium has a valence of three which comprises reacting in an inert atmosphere and at a temperature of at least 100° C. titanium monoxide, an alkali metal fluoride and an acid fluoride of the group consisting of sodium, potassium, lithium and ammonium acid fluorides, and recovering the resulting alkali metal fluotitanate of trivalent titanium.

2. The method of producing alkali metal fluotitanates in which the titanium has a valence of three which comprises reacting in an inert atmosphere and at a temperature of about 100°-125° C. titanium monoxide, an alkali metal fluoride and an acid fluoride of the group consisting of sodium, potassium, lithium and ammonium acid fluorides, subsequently raising the temperature of the resulting mass to about 400°-500° C. to complete the reaction, and recovering the resulting alkali metal fluotitanate of trivalent titanium.

3. The method of producing alkali metal fluotitanates in which the titanium has a valence of three which comprises reacting in an inert atmosphere and at a temperature of at least 100° C. titanium monoxide, an alkali metal fluoride and ammonium acid fluoride, and recovering the resulting alkali metal fluotitanate of trivalent titanium.

4. The method of producing alkali metal fluotitanates in which the titanium has a valence

5 of three which comprises reacting in an inert atmosphere and at a temperature of about 100°-125° C. titanium monoxide, potassium fluoride and ammonium acid fluoride, subsequently raising the temperature of the resulting mass to about 400°-500° C. to complete the reaction, and recovering the resulting potassium fluotitanate of trivalent titanium.

10 5. As a new composition of matter, a titanium compound of the formula $M_nTi_{n'}F_{n''}$ in which M is an alkali metal, n is at least 2 and not over 3, n' is at least 1 and not over 2, n'' is at least 6 and not over 8, and in which $n+3n'=n''$, said compound being non-hygroscopic and resistant against oxidation.

15 6. As a new composition, a titanium compound K_3TiF_6 , being non-hygroscopic and resistant against oxidation.

7. As a new composition, a titanium compound 20 $K_2Ti_2F_8$, being non-hygroscopic and resistant against oxidation.
